UNITED STATES PATENT OFFICE.

THOMAS WILLIAM MILLS AND JOHN ERNEST CUNNINGHAM, OF KINGSTON,
CANADA.

SAVINGS-BANK.

SPECIFICATION forming part of Letters Patent No. 725,858, dated April 21, 1903.

Application filed June 5, 1902. Serial No. 110,356. (No model.)

To all whom it may concern:

Be it known that we, THOMAS WILLIAM MILLS and JOHN ERNEST CUNNINGHAM, bankers, of the city of Kingston, in the county of 5 Frontenac, in the Province of Ontario, Canada, have invented certain new and useful Improvements in Savings-Banks, of which the following is a specification.

Our invention relates to improvements in 10 savings-banks which are specially intended for home use and are issued by bankers or banks to their customers to assist them in saving their money; and the object in inventing this bank is to make a savings-bank 15 which shall be extremely cheap and simple in construction and from which it will be absolutely impossible to extract either coins or paper money which may have been inserted therein without having access to the bank by 20 means of a key or other lock; and it consists, essentially, of a box having a suitable door provided in one of its sides and a slot sufficiently large to admit the largest coin and an opening for inserting bills, means being pro- 25 vided for preventing the withdrawal of the coins or the bills after having been inserted in the bank, the various parts being constructed and arranged in detail, as hereinaf- 30 ter more particularly described.

Figure 1 is a perspective view of one-half of our savings-bank, being cut through the middle on the line X X, Fig. 2. Fig. 2 is a transverse section of our savings-bank on the line Y Y, Fig. 1. Fig. 3 is a detail perspective view of the means for preventing the removal of coins from the bank. Fig. 4 is a detail of the tube for preventing the removal of bills with the auxiliary pivotal tooth. Fig. 5 is a cross-sectional view of the tube through 40 which bills are introduced.

In the drawings like letters of reference indicate corresponding parts in each figure.

A is the box or casing for the bank, and this casing may be of a variety of forms, 45 whether square, oblong, cylindrical, or any other suitable shape, the form shown, however, being the one which we consider preferable. A handle a may be provided on the top of the box.

a' is a door which is secured by hinges in one of the sides or one of the ends or the bot-

tom of the box and may be locked by any suitable means.

For the sake of clearness throughout the specification and claims the end a² of the box 55 will be referred to as the "forward" end and the end a³ will be called the "rear" end.

An opening B is formed in the box, preferably at the rear end, and this opening may be of any suitable form, though it is preferably circular. A tube b extends inwardly from the hole or orifice B and is provided at its inner end with inwardly-pointing teeth b'. In Fig. 4 an auxiliary tooth b² is shown on the tube b, the said tooth being suitably pivoted at b³ to the upper side of the tube b and depends through a slot b⁴ into the tube. The tube b is preferably curved, as shown, in order to make it more difficult and practically impossible to insert any instrument 60 through to remove the paper money from the bank. It will thus be seen that a bill may be folded tightly and passed through the tube b into the bank; but once it is past or any portion of it is past the teeth b' it cannot be 65 withdrawn from the bank without tearing or mutilating the bill to such an extent as to render it worthless.

C is a slot formed in the upper portion of a side or end of the box. A shelf or platform c 80 extends inwardly from the slot C, the inner end of the said shelf being preferably at a distance from the rear end of the box just equal to or slightly greater than the diameter of the largest coin for which the bank will be 85 used.

c' is a second shelf or platform, which is slightly lower than the shelf c, the distance between these shelves at their nearest point being just sufficient to permit the thickest 90 coin passing freely between them. The shelf c' extends from the back of the bank, or, in other words, from the end of the bank opposite to the slot C toward the forward end of the bank and is preferably sloped downwardly. Between the shelf c' and the shelf c a plate c² is provided, thus forming with the shelf c' an inner passage or chute c³, through which the coins will pass. This chute terminates, preferably, at a distance from the 95 front end of the box slightly greater than half the diameter of the largest coin which 100

will be used in the bank. A lip c^4 is formed completely around the outlet of the chute c^3 .

D is a tube or bottomless bag which may be made of any suitable flexible material, but 5 is preferably made of very light silk. This flexible tube is secured over the outlet c^5 by suitable means, such as a cord c^6 , passing around the outside of the chute c^3 behind the lip c^4 . It will thus be seen that a coin may 10 be inserted in the slot C, and by tilting the forward end of the bank first upwardly and then downwardly the coin will slide in along the platform c and drop onto the shelf c' and will then slide back through the chute c^3 and 15 the tube D, thus dropping to the floor or bottom of the bank. The tube or bottomless bag D makes it absolutely impossible to shake a coin back into the chute c^3 , for if the bank be reversed bottom side up the coin will 20 simply drop on the bag and force it into the corner between the opening c^5 and the front of the bank, thus completely closing the opening c^5 . In order to make the closure of the opening 25 doubly secure, a swinging weight d' may be suspended near the flexible tube D, either inside or outside, by suitable means, so that if the bank be reversed the said weight will fall either in front of the hole or behind it, carrying the flexible tube with it, and thus completely covering the hole. 30

It may be mentioned that the object in view in constructing the passage or chute as above is chiefly to prevent the insertion of a hooked or V-shaped instrument for the purpose of holding open the flexible tube while the coins are being removed from the bank. It will be noticed that the distance between the 35 edge of the shelf c and the rear end of the bank is considerably less than the distance 40 from the edge of the said shelf to the opening c^5 . It will thus be seen that if a V-shaped instrument having a short and a long end were inserted through the slot C the small end could not be greater than the distance from the end 45 of the shelf c to the rear of the box; but this length would obviously be too short to reach the end of the shelf c to the opening c^5 , and consequently the flexible tube could not be held open by such an instrument to enable 50 coins to be removed.

It will now be seen that we have invented a bank from which it will be impossible to remove either coins or paper money; but although in the drawings we have shown the 55 form of the apparatus which we consider preferable it is to be understood that a considerable number of changes may be made in the details of the device without departing from the spirit of our invention. For example, the 60 inwardly-extending tube B might be placed in any suitable part of the bank and not in the exact position shown in the drawings. Also this tube might be made angular instead of curved. The position of the device for preventing the removal of coins might also be varied. 65

Another variation which might be made in

the construction would be to have the door formed in the bottom of the bank instead of the side, as shown, and in this case the side 70 piece c^7 would be close up to the side of the box.

Although the device at the front of the bank is intended chiefly to prevent the removal of coins therefrom, it will be understood that this device may be used to prevent the removal of bills or other money or car-fares from a fare-box, and the curved tube at the rear end of the box could be used for preventing the removal of any articles—such 80 as car-tickets, ballots, or the like—from receptacles.

Although we have described our invention as relating particularly to savings-banks, it is to be understood that the same device may 85 be applied to other receptacles—such as mail-bags, ballot-boxes, fare-boxes, and the like—without exceeding the scope of our invention.

What we claim as our invention is—

1. In a device of the class described, the combination with the receptacle having an orifice in one of the walls thereof, of a rigid tube of circular cross-section extending inwardly from the orifice, and a circular row 95 of integral teeth on the inner end of said tube, substantially as described.

2. In a device of the class described the combination with the receptacle having an orifice formed in one of its walls, of a rigid 100 tube of circular cross-section extending inwardly from said orifice and having a circular row of inwardly-pointing teeth formed integral therewith at its inner extremity, and having a slot formed in its upper side, a pointed tooth pivotally secured to the upper side 105 of said tube and designed to depend through said slot into said tube as and for the purpose specified.

3. In a device of the class described the combination with the receptacle having a slot 110 and a flexible tube therein for preventing the removal of coins or other articles contained in the receptacle through the slot, of means interposed between the slot and the flexible 115 tube for preventing the insertion of an instrument into the flexible tube as and for the purpose specified.

4. In a device of the class described, the combination with a receptacle having a slot 120 formed on one of its walls, of a chute extending from said slot to the opposite end of the receptacle and a return-chute extending from the rear end of the receptacle to a point in proximity to the forward end thereof, said 125 return-chute being substantially parallel with the first-mentioned chute and a tube of flexible material secured over the inner mouth of said return-chute as and for the purpose specified.

5. In a device of the class described, the combination with a receptacle having a slot formed in one of its walls in proximity to the top of the receptacle, of a shelf extending

from the lower edge of said slot toward the opposite end of the receptacle, said shelf being approximately parallel to the top of the receptacle, and a lower shelf located below 5 said upper shelf and being approximately parallel thereto, said lower shelf extending from the rear end of the receptacle toward the forward end thereof, thus forming a return-chute beneath the upper shelf, the distance 10 between the rear end of the receptacle and the rear edge of the upper shelf being less than the distance between the rear edge of the upper shelf and the forward end of the lower shelf, and a flexible tube secured over 15 the opening at the end of said chute as and for the purpose specified.

6. A savings-bank comprising a box hav-

ing a coin-opening at one end and a paper-money opening or orifice at its opposite end, a rigid tube extending into the box from said 20 paper-money orifice and having teeth at its inner extremity, and a passage extending rearwardly from the coin-slot to the opposite end of the box and then forwardly, and a flexible tube secured over the opening at the 25 end of said passage as and for the purpose specified.

Signed at the city of Kingston this 30th day of May, 1902.
